UNITED STATES PATENT OFFICE.

ERNEST SCHLICKER, OF PITTSBURG, PENNSYLVANIA.

TROLLEY-POLE.

SPECIFICATION forming part of Letters Patent No. 732,967, dated July 7, 1903.

Application filed February 21, 1903. Serial No. 144,399. (No model.)

To all whom it may concern:

Be it known that I, ERNEST SCHLICKER, a citizen of the United States, residing at Pittsburgh, in the county of Allegheny and State of Pennsylvania, have invented a new and useful Improvement in Trolley-Poles, of which improvement the following is a specification.

This invention relates to an improved trolley-pole for street-railway purposes; and it consists in the certain details of construction and combination of parts, as will be fully described hereinafter.

In the accompanying drawings, Figure 1 is a front elevation of my improved trolley-pole, which is constructed and arranged in accordance with my invention. Fig. 2 is a side elevation of the same.

To put my invention into practice with a street-railway car or other vehicle propelled by electricity from an overhead wire or conductor 5, I arrange upon the top of the car a base-plate 9, having bearings 1 at either side thereof, in which is mounted a shaft 2, carrying the trolley-pole 3, the top of which is curved, as at 4, Fig. 1 of the drawings. Attached to the outer ends of the shaft 2 are double cranks 6, held rigid with the said shaft by set-screws 7' and each crank connected to two springs 8, one at either side, the other ends of which are attached to posts 10, formed integral with the base-plate 9, the said springs 8 being connected and arranged in a manner to place a tension upon the trolley-pole 3 and keep the same in a vertical position when free from the line-wire 5.

In operation the trolley-pole 3 and its base have a vertical reach slightly greater than the distance between the top of the car and the line-wire 5, thereby causing the pole when in contact with the said wire to assume a slightly-inclined position, as shown at Fig. 2 of the drawings. The top or contact portion 4 of the trolley-pole is in practice about five feet wide, which will permit side movement

and keep its contact when the vehicle is passing around curves, and by reason of the springs 8 the trolley will at all times keep a close contact with the line-wire 5. Attached to the frame of the trolley are two ropes 3', leading to either end of the car, by means of which the operator may change the angle of the frame or reverse the pole.

It is obvious from the foregoing description, taken in connection with the accompanying drawings, that by this construction and arrangement of a trolley-pole the contact portion 4 cannot leave the wire 5 under any ordinary condition.

Various slight modifications and changes may be made in the details of construction without departing from the spirit of the invention.

Having thus described my invention, what I claim, and desire to secure by Letters Patent, is—

In a device of the character described, the combination of a base-plate, bearings on either side thereof, a shaft mounted in said bearings, and having its ends projecting therethrough, bell-cranks mounted on said ends of said shaft, means for securing said bell-crank on said ends of said shaft, lugs integral with said base-plate arranged on opposite sides of said bearings, springs connected to said bell-cranks and to said lugs, and a trolley-pole comprising a frame integral with said shaft, the upper portion of said trolley-pole being formed with a laterally-extended loop having a segmentally-formed upper surface, substantially as described.

In testimony whereof I have hereunto signed my name in the presence of two subscribing witnesses.

ERNEST SCHLICKER.

In presence of—
F. O. HENZI,
M. HUNTER.
